(57) **CLAIM**

The ornamental design for a seating, as shown and described.

DESCRIPTION

FIG. 1 is an isometric view of a seating showing a first embodiment of my new design.

FIG. 2 is a left side elevational view of the seating of FIG. 1, the right side elevational, front elevational, and back elevational views being identical thereto.

FIG. 3 is a top plan view of the seating of FIG. 1.

FIG. 4 is a bottom plan view of the seating of FIG. 1.

FIG. 5 is a side elevational view rotated approximately 45 degrees from the side elevational view of FIG. 2.

FIG. 6 is an isometric view of a seating showing a second embodiment of my new design.

FIG. 7 is a left side elevational view of the seating of FIG. 6, the right side elevational, front elevational, and back elevational views being identical thereto.

FIG. 8 is a top plan view of the seating of FIG. 6.

FIG. 9 is a bottom plan view of the seating of FIG. 6.

FIG. 10 is a side elevational view rotated approximately 45 degrees from the side elevational view of FIG. 7.

FIG. 11 is an isometric view of a seating showing a third embodiment of my new design.

FIG. 12 is a left side elevational view of the seating of FIG. 11, the right side elevational, front elevational, and back elevational views being identical thereto.

FIG. 13 is a top plan view of the seating of FIG. 11.

FIG. 14 is a bottom plan view of the seating of FIG. 11; and, FIG. 15 is a side elevational view rotated approximately 45 degrees from the side elevational view of FIG. 12.

The broken line showing of a table and legs joining the seats to the table in FIGS. 1-15 are included for the purpose of illustrating use and environment and form no part of the claimed design.
